Patented Feb. 20, 1917.

UNITED STATES PATENT OFFICE.

GEORGE L. HARRISON, OF EAST CLEVELAND, OHIO, ASSIGNOR TO THE CLEVELAND METAL PRODUCTS COMPANY, OF CLEVELAND, OHIO, A CORPORATION OF OHIO.

HANDLE.

1,216,309.

Specification of Letters Patent. Patented Feb. 20, 1917.

Application filed April 23, 1915. Serial No. 24,384.

To all whom it may concern:

Be it known that I, GEORGE L. HARRISON, a citizen of the United States, residing at East Cleveland, in the county of Cuyahoga and State of Ohio, have invented a certain new and useful Improvement in Handles, of which the following is a full, clear, and exact description, reference being had to the accompanying drawings.

This invention relates to an improved handle that is especially suitable for use in connection with cooking utensils, and particularly to a handle of this class that is formed of pressed metal parts.

The invention has for its objects to provide a handle that is simple of construction, yet very rigid, and is comparatively cheap of production; to provide a handle of the above mentioned character that is comfortable to the hand of the user, and is of such nature as will tend to reduce to a minimum the transmission of heat from the object or utensil to which it is connected, to the grip portion of the handle; that comprises a plurality of parts connected in a manner that is very simple, effectual and extremely economical, and which renders the substantialness of the handle unaffected by any degree of heat to which the handle is liable to be subjected in the use of the utensil of which it forms a part.

The foregoing objects, and others which will become apparent as this description proceeds, are attained in a handle constructed in accordance with the accompanying drawing which forms a part hereof; and while I will proceed to describe the handle shown in said drawing in detail, I wish to be understood as not limiting myself to the structural details thereof further than is required by the terms of the annexed claims and is rendered necessary by the state of the prior art.

In the drawings, Figure 1 is a perspective view of my improved handle; Fig. 2 is a longitudinal section through the same; Fig. 3 is a transverse section through the handle on the line 3—3 of Fig. 2; and Figs. 4 and 5 are developments of the two blanks of which the handle is composed.

It will be observed from Fig. 4 that the blank of member A comprises a supporting plate 1 that is triangular in shape, and from the base of which there extends a tongue 2 which, as will be explained presently, con-

stitutes a part of the grip of the complete handle. The other member B of the grip is formed by the blank shown in Fig. 5.

I have shown in dotted lines in Figs. 4 and 5, the lines on which the blanks are bent into their ultimate form, and as will be clearly seen from Figs. 2 and 3, the supporting plate 1 of member A is bent at substantially right angles to the tongue 2, and that the periphery of the tongue is bent downward to form a flange 3, the central portion of the tongue being curved upward transversely and also from its free end to within a short distance of where it has connection with the plate 1. Here the tongue is curved downward into the plane of the upper end of the supporting plate, as shown at 4 in Fig. 2, the corresponding portion of the blank of Fig. 4 being inclosed by dotted lines, and having the same reference numeral applied to it. The corners of the supporting plate are provided with perforations 5 for the reception of suitable securing means, such as rivets, for attaching the handle to cooking utensils, or other objects wherewith it is employed. The material of the supporting plate is depressed about the perforations 5, as shown at 6, and the upper depressed portions are connected to the lower one by beads 7. By thus beading the supporting plate it is rendered very rigid, and permits of the use of comparatively light stock in the production of a handle of maximum strength. The free end of the tongue 2 is perforated at 8, and the material which surrounds it is pressed downward to form a neck 9.

The member B of the handle is curved transversely in the reverse direction from the curvature of the tongue 2, and its outline is identical with the periphery of the tongue, just inside the flange 3, except where the member B is bent downward and curved toward the supporting plate 1, as shown at 10. The extreme end of the member B is preferably turned down to form a flange 11 that bears against the surface of the supporting plate 1, and the opposite end of the member is perforated at 12, and the material surrounding the perforation, indicated at 13, is bent upward substantially on the dotted line of Fig. 5. When the parts are assembled, the perforation 12 of member B receives the neck 9 of the other member and said neck is flared out against the di-

verging sides of the portion 13 and assists in holding the members together. The members are positively held against separation throughout their lengths by the flange 3 that is pressed inward about the side edges of the member B.

If found desirable, the flange 11 may be welded, or otherwise secured to the supporting plate 1; but I find it practicable to tin the handle after it has been assembled, and the tin coating thoroughly fills the joints between the members and assists in holding them together. However, other finishes, such as japan, enamel, or the like, may be substituted for the tin, and besides this having the beneficial effect just mentioned, it provides a very economical method of finishing the handles.

It will be readily understood from the foregoing description that the member B constitutes a very rigid brace or bracket having a shape that will enable it to effectually resist the force of compression to which it is subjected when a vessel is lifted by the handle; and that the tongue 2 is placed under tension during such an operation, and because of its integral connection with the plate 1, is highly capable of withstanding the stress under which it is placed.

Having thus described my invention, what I claim is:—

1. A handle comprising a supporting plate that is provided with a series of perforations, the material of the plate being depressed about the perforations and beaded therebetween, a tongue extending laterally from the supporting plate, and a member

40 applied to the underneath side of the tongue and having a portion which bears against the supporting plate.

2. A handle comprising a supporting plate that is substantially triangular in shape, the plate having a perforation in each of its corners and having the material surrounding said perforations depressed, a tongue extending laterally from one edge of the plate, the plate having beads which extend from the vicinity of the edge to which the tongue is connected to the corner that is opposed to such edge, and a member applied to the 45 underneath side of the tongue, and having a portion which engages the supporting plate.

3. A handle comprising a substantially 50 triangular supporting plate that has a perforation in each of its corners, the material surrounding the perforations being depressed, the plate having beads that extend substantially parallel to two of its sides and between certain of the foregoing depressed 55 portions, a tongue formed integral with and extending at substantially right angles from the other side of the supporting plate, and a member that is applied to the underneath side of the tongue and having a portion that 60 engages the supporting plate at a point spaced below the plane of the tongue.

65 In testimony whereof, I hereunto affix my signature in the presence of two witnesses.

GEORGE L. HARRISON.
